UNITED STATES PATENT OFFICE.

JOHN E. KENNEDY AND CLARENCE E. MORFORD, OF DAYTON, OHIO.

SWITCH FOR ELECTRIC CIRCUITS.

Application filed August 20, 1923. Serial No. 658,312.

This invention relates to a switch for electric circuits and is designed more particularly for use in controlling the lights of an automobile or the like.

5 One object of the invention is to provide a switch by means of which the various lighting circuits may be conveniently controlled to cause such of said lamps as may be desired to be illuminated.

10 A further object of the invention is to provide a device of this kind which may be set to close the circuit to the headlights and then shifted to close the circuit to the dimmers without altering the position of the 15 setting means.

20 A further object of the invention is to provide a switch of this kind which will be simple in its construction and operation and which will be of such a character that the 25 parts thereof will not be easily disarranged or rendered inoperative.

Other objects of the invention will appear as the device is described in detail.

25 In the accompanying drawings Fig. 1 is a plan view of a switch embodying our invention; Fig. 2 is a section taken on the line 2—2 of Fig. 1; Fig. 3 is a bottom plan view of the switch; Fig. 4 is a front elevation of the same; Fig. 5 is a section taken on the line 30 5—5 of Fig. 1; Fig. 6 is a section taken on the line 6—6 of Fig. 1; and Fig. 7 is a section taken on the line 7—7 of Fig. 2.

35 In these drawings we have illustrated one embodiment of our invention but it will be understood that this embodiment has been chosen for the purposes of illustration only and that the device may take various forms without departing from the spirit of the invention.

40 As here shown the switch comprises a main frame consisting of a base 1, a front wall 2, a rear wall 3 and an intermediate wall or partition 4, the walls 2, 3, and 4 being preferably arranged parallel and being 45 spaced one from the other. Preferably this main frame is formed from a single piece of metal the lateral portions of which are bent upwardly to form the front and rear walls, and the base of which is cut away between 50 the back wall and the intermediate wall 4 to form an opening 5 in the base and the material thus cut away is bent upwardly to form the intermediate wall 4. Rigidly secured to the base 1 beneath the opening 5 55 therethrough is a plate of insulating material 6 on which are mounted a plurality of

fixed contact members. In the present instance, there are four of these contact members each of which constitutes a binding post extending through the insulating plate and having its upper end shaped to constitute a contact member. If desired, an ordinary brass screw may be passed through the insulating plate with its head above the same and provided with nuts by means of which the conductor may be attached thereto. In the present construction these four contact members are shown at 7, 8, 9 and 10. The contact member 7 is connected with the head light circuit, the contact member 8 is connected with the dimmer circuit, the contact member 9 is connected with the tail light circuit and the contact member 10 is connected with the circuit for a parking light or such auxiliary light as may be employed on the machine. Mounted on the insulated base plate 6 and arranged above the respective contact members 7, 8, 9 and 10, are a plurality of movable contact members. In the present instance, these movable contact members are formed from a single piece of resilient metal, as shown at 11, which is carried by an insulating block 12 mounted on the insulating plate 6 between the ends thereof. As here shown, the plate 11 is secured in position by means of a bolt 13 passing through the block 12 and the insulating plate 6. The bolt projects some distance below the insulating plate and is provided with nuts 14 for attaching the conductor thereto, thus constituting the bolt a binding post. The plate 11 is bifurcated on each side of its point of connection with the plate 6 so as to provide the same with four contact members, as shown at 15, 16, 17 and 18. 90 These contact members being formed of resilient metal they will be normally supported in positions above but out of contact with the respective fixed contact members but may be readily pressed downward into engagement with the respective contact members to establish an electrical connection between the same and the plate 11, which will be connected with a battery or other source of electrical current. It will be apparent, therefore, that when the several movable contact members are unrestrained they will occupy inoperative positions with relation to the fixed contact members and all the circuits 95 will be broken.

100 Suitable operating devices are provided for depressing selected movable contact

members to close the circuit through selected lamps and these actuating devices are of such a character that the circuits may be closed individually or in certain groups.

5 The actuating devices may take various forms but, in the present instance, we have provided two levers, 19 and 20, which are pivotally mounted between their ends on a shaft, or bolt, 21 mounted in the back wall 3 and intermediate wall 4 of the main frame and arranged a short distance above the contact plate 11. Each lever extends parallel with one pair of contact arms, 15 and 16, and 17 and 18, and is provided at its ends 10 with means, preferably in the form of blocks of insulating material, as shown at 22, to engage and actuate the corresponding movable contact members. The two actuating levers are mounted for movement about the same axis, are similar in construction and are independently operable, but the means for controlling the positions of these levers is such that they may be operated either independently or simultaneously according to 15 the grouping of circuits desired. Preferably the levers are acted upon by springs which tend to move the same in one direction and means are provided for controlling the movement of these levers by the springs and 20 for moving the same against the tension of the springs. In the present construction each lever is provided with an arm extending upwardly therefrom, the lever 20 having an arm 23 extending a short distance above 25 the same and connected by a spring 24 with a fixed part of the frame, such as a lug 25, carried by the intermediate wall 4. The arm 26 which extends upwardly from the lever 19 is of greater length than the arm 23 and is connected by a link 27 with a rock arm 28 mounted on a shaft 29 journaled in the front and rear walls of the main frame. The rock arm 28 is provided with a bracket 30 which is connected by means of a spring 31 with a fixed part of the main frame, such as a lug 32 carried by the base 1, the action of this spring being such as to move the rock arm 28 and consequently the arm 26 40 of the lever 19 toward the left in the drawings. The means for controlling the movement of the levers by the springs may take various forms but for convenience of operation we prefer to utilize a rotating device having cam surfaces arranged in line with the arms 23 and 26 and the positions of which, with relation to said arms, will control the positions of the actuating levers 19 and 20. In the present construction, a shaft 33 is rotatably mounted in the walls 2, 3 and 4, of the frame and is provided on that portion adjacent to the edges of the arms 23 and 26 with cam shaped portions, which portions are adapted to engage the respective arms and to limit their movement under the influence of the springs or to move them 45 against the tension of the springs. The shaft 33 extends through the front wall 2 and is provided with an actuating knob or handle 34 and also has connected therewith a pointer 35 which is adapted to travel over an indicator or dial formed on the outer surface of the front wall 2, which constitutes the face plate of the switch. This dial is provided with a plurality of letters or markings to indicate the connections which will be established when the pointer is in a given position and preferably the face plate is provided adjacent to each indication with a recess 36 adapted to receive the inturned end of the pointer and secure the same 50 against accidental displacement. Stops or pins 37 project from the face plate to limit the rotation of the shaft 33. In order that the inturned end of the pointer 35 may be moved into and out of a recess 36 a spring 38 is coiled about the rear end of the shaft 33, which projects beyond the back plate 3 and is confined between said back plate and a stop or washer 39 mounted on the rear end of the shaft. Thus a forward pull on the knob 34 will disengage the pointer from the recess in which it is seated and when the knob is released the pointer will be pressed against the face plate and if it is in line with a recess will be moved into that recess. In 55 the present construction, the shaft 33 is not provided with separate cam members but has those portions thereof adjacent to the edges of the arms 23 and 26 cut away to impart to the shaft itself shapes which will properly control the two arms. The particular shapes of these portions of the shaft will be determined by the positions in which the levers are to be retained by the shaft. In the present arrangement of the mechanism the cam surfaces are of such a character that when the pointer 35 is in its neutral or zero position, as shown in Fig. 4, the arms 23 and 26 will be held in such positions that the levers 19 and 20 will be substantially horizontal, consequently none of the movable contact members will be depressed. If the pointer is moved to position B on the dial both arms 23 and 26 will be permitted to 60 move under the influence of the springs 24 and 31 to the left, thereby depressing the contact members 15 and 17 and closing the circuits through the head lights and through the tail light. If the pointer is moved to the position T on the dial the arm 26 will be forced back to its neutral position but the arm 23 will remain in a position to hold the circuit closed through the tail light. If the pointer is advanced to position P, the arm 23 will be restored to its neutral position and moved past that position to depress the contact member 18 to close the circuit to the parking light. In the present construction, this is the last position to which the pointer 65 can be moved in this direction. If the 115

120

125

130

pointer is moved from zero to position D the arm 26 will be moved to the right to depress the contact member 16 and close the circuit to the dimmers and at the same time 5 the arm 23 will be permitted to move to the left to depress the contact member 17 and close the circuit through the tail light. In driving an automobile with powerful head lights it is frequently necessary to dim 10 the head lights to avoid interfering with a driver of an approaching vehicle and in the application for patent filed April 25, 1923, by John E. Kennedy, Serial No. 634,530, there is shown an apparatus designed to be 15 operated by the knee of the driver for quickly and easily dimming the head lights and then restoring them to their full illumination. The present switch is particularly adapted for use in connection with this device and to this end we have rigidly secured the rock arm 28 to the shaft 29 and have extended this shaft through the front wall 2 of the frame and have provided the same with an actuating member 40 which is designed 20 for operative connection with the controlling mechanism of the above mentioned application. That controlling mechanism preferably comprises a rock shaft 41 mounted in suitable brackets arranged at 25 the side of the car and provided with a depending arm 42 arranged adjacent to the driver's knee so that a slight lateral movement of the knee will rock the shaft 41. Rigidly secured to the shaft 41 is a second 30 rock arm 43 the upper end of which is connected with, or in engagement with, the actuating member or arm 40 in such a manner as to cause that arm to rock the shaft 29 in a direction to move the arm 26 of the lever 35 19 to the right in the drawings and thus release the contact member 15 which closes the circuit through the head lights and actuate the contact member 16 to close the circuit to the dimmers. This is accomplished 40 without shifting the position of the cam shaft by simply forcing the arm away from the cam surface and against the tension of the spring 31. As soon as the pressure on the controlling device is relieved the spring 45 45 will restore the lever 19 to its original position, thereby cutting out the dimmers and again brightly illuminating the head lights. This shifting of the circuit can be accomplished very quickly and very easily 50 and the head lights are entirely dark but for a very brief instant. To protect the switch against injury due to the violent operation of the controlling device we have established a yielding connection between 55 the rock arm 28 and the link 27 which connects the same with the arm 26. As here shown the upper end of the rock arm 28 is slidably mounted on the link 27 and a spring 45 is coiled about the link and confined 60 between the arm 28 and a stop 46 se- cured to the link. This spring is of sufficient stiffness to cause the link and arm 26 to be actuated by the rock arm but will yield in case excessive pressure is applied to the rock arm, before the switch is injured. 70

While we have shown and described one embodiment of our invention we wish it to be understood that we do not desire to be limited to the details thereof as various modifications may appear to a person skilled 75 in the art.

Having now fully described our invention, what we claim as new and desire to secure by Letters Patent, is:

1. In a device of the character described, 80 a plurality of contact members, a corresponding plurality of movable contact members held normally out of engagement with the respective first mentioned contact members, a pivoted actuating device having parts to engage and actuate the respective movable contact members, a spring acting on said device to move the same in one direction, and means to control the movement of said device by said spring, said controlling means being so arranged that when moved to one position it will retain said actuating device in an intermediate position, when moved to another position it will permit said actuating device to be moved by 85 said spring, and when moved to a third position it will cause said actuating device to be moved against the action of said spring and beyond said intermediate position. 90

2. In a device of the character described, 100 a plurality of contact members, a corresponding plurality of movable contact members held normally out of engagement with the respective first mentioned contact members, a lever pivotally mounted between its ends on an axis arranged between two of said movable contact members and having parts to engage and actuate the respective movable contact members, a spring acting on said lever to move the same in one direction, and a cam acting as a stop to limit the movement of said lever by said spring and to move said lever in the opposite direction against the tension of the said spring. 105

3. In a device of the character described, 110 a plurality of contact members, a corresponding plurality of movable contact members held normally out of engagement with the respective first mentioned contact members, a lever pivotally mounted between its ends on an axis arranged between two of said movable contact members and having parts to engage and actuate the respective movable contact members, an arm extending 115 upwardly from said lever adjacent to the axis thereof, a spring acting on said arm to move said lever about its axis, and a rotatable member arranged adjacent to said arm and having cam surfaces to engage said arm 120 and limit the movement of said lever by said 125

130

spring and to move said lever against the action of said spring.

4. In a device of the character described, a plurality of contact members, a corresponding plurality of movable contact members held normally out of engagement with the respective first mentioned contact members, a lever pivotally mounted between its ends on an axis arranged between two of said movable contact members and having parts to engage and actuate the respective movable contact members, an arm extending upwardly from said lever adjacent to the axis thereof, a spring acting on said arm to move said lever about its axis, and a shaft extending transversely to said arm and having portions thereof cut away to provide cam surfaces to control the position of said arm.
5. In a device of the character described, a plurality of contact members, a corresponding plurality of movable contact members held normally out of engagement with the first mentioned contact members, two independent levers pivotally mounted adjacent to said movable contact members and each having parts to engage the respective movable contact members and actuate the same, and means to cause said levers to move either in unison or relatively one to the other.
6. In a device of the character described, a plurality of contact members, a corresponding plurality of movable contact members held normally out of engagement with the first mentioned contact members, two independent levers pivotally mounted adjacent to said movable contact members and each having parts to engage the respective movable contact members and actuate the same, a spring acting on each lever to move the same in one direction, and a manually actuated device to control the movement of said levers by said springs and to move said levers against the action of said springs either in unison or with relation one to the other.
7. In a device of the character described, a plurality of contact members, a corresponding plurality of movable contact members held normally out of engagement with the first mentioned contact members, two independent levers pivotally mounted adjacent to said movable contact members and each having parts to engage the respective movable contact members and actuate the same, a spring acting on each of said levers to move the same in one direction, and a rotatable member having cam shaped portions acting on said levers to cause the same to be moved either in unison or with relation one to the other.
8. In a device of the character described, a plurality of contact members, a corresponding plurality of movable contact mem-

bers held normally out of engagement with the first mentioned contact members, two independent levers pivotally mounted between their ends and each having at its respective ends parts to engage the corresponding movable contact members and actuate the same, springs acting on said levers to move the same in one direction, arms rigidly secured to and extending upwardly from the respective levers near their axes, and a shaft extending transversely to said arms and having cam shaped portions to engage the edges of the respective arms to control the positions of said levers.

9. In a device of the character described, a plurality of contact members, a corresponding plurality of movable contact members held normally out of engagement with the respective first mentioned contact members, an actuating device comprising parts arranged to engage and actuate the respective movable contact members, means comprising a cam to control the position of said actuating device, and means for imparting movement to said actuating device with relation to said controlling means.

10. In a device of the character described, a plurality of contact members, a corresponding plurality of movable contact members held normally out of engagement with the respective first mentioned contact members, a pivoted actuating device having parts to engage and actuate the movable contact members, means to control the position of said actuating device, and other means to move said actuating device relatively to said controlling means.

11. In a device of the character described, a plurality of contact members, a corresponding plurality of movable contact members held normally out of engagement with the respective first mentioned contact members, a lever pivotally mounted between its ends on an axis arranged between two of said movable contact members and having parts to engage and actuate the respective movable contact members, an arm extending above said lever near the axis thereof, a spring acting on said arm to move the same in one direction, a rotatable member having cam surfaces to control the movement of said arm by said spring and to move the same against the tension of said spring, and other means for actuating said arm against the tension of said spring to move said arm away from the first mentioned controlling device.

12. In a device of the character described, a plurality of contact members, a corresponding plurality of movable contact members held normally out of engagement with the respective first mentioned contact members, a lever pivotally mounted between its ends on an axis arranged between two of said movable contact members and having

parts to engage and actuate the respective movable contact members, an arm extending above said lever near the axis thereof, a spring acting on said arm to move the same 5 in one direction, a rotatable member having cam surfaces to control the movement of said arm by said spring, and to move the same against the tension of said spring, a rock arm operatively connected with the arm 10 of said lever, and an actuating member for imparting movement to said rock arm.

13. In a device of the character described, a plurality of contact members, a corresponding plurality of movable contact members held normally out of engagement with the respective first mentioned contact members, a lever pivotally mounted between its ends on an axis arranged between two of said movable contact members and having 20 parts to engage and actuate the respective movable contact members, an arm extending above said lever near the axis thereof, a spring acting on said arm to move the same in one direction, a rotatable member having 25 cam surfaces to control the movement of said arm by said spring and to move the same against the tension of said spring, a rock shaft, an arm secured to said rock shaft, a link connecting the last mentioned 30 arm with the arm of said lever, and an actuating member connected with said rock shaft.

14. In a device of the character described, a plurality of contact members, a corresponding plurality of movable contact members held normally out of engagement with the respective first mentioned contact members, a lever pivotally mounted between its ends on an axis arranged between two of 35 said movable contact members and having parts to engage and actuate the respective movable contact members, an arm extending above said lever near the axis thereof, a spring acting on said arm to move the same 40 in one direction, a rotatable member having cam surfaces to control the movement of said arm by said spring and to move the same against the tension of said spring, a rock shaft, an arm secured to said rock shaft, a link connecting the last mentioned arm 45 with the arm of said lever, an actuating member connected with said rock shaft, and a yieldable connection between the last mentioned arm and said link.

15. In a device of the character described, a plurality of pairs of contact members, a corresponding plurality of pairs of movable contact members, separate actuating devices for the respective pairs of movable contact 50 members, means for controlling the positions of said actuating devices, and other means for moving one of said actuating devices with relation to said controlling means.

16. In a device of the character described,

a plurality of pairs of contact members, a corresponding plurality of pairs of movable contact members, separate actuating devices for the respective pairs of movable contact members, a spring acting on each actuating 70 device, a manually operated device to control the movements of said actuating devices by the respective springs and to move said actuating devices against the action of said springs, and means to move one of said actuating devices independently of said manually operated device.

17. In a device of the character described, a plurality of contact members, a corresponding plurality of movable contact members held normally out of engagement with the first mentioned contact members, two independent levers mounted adjacent to said movable contact members and each having parts to engage the corresponding movable 85 contact members and actuate the same, means for controlling the positions of said levers, and other means for moving one of said levers relatively to said controlling means.

18. In a device of the character described, a plurality of contact members, a corresponding plurality of movable contact members held normally out of engagement with the first mentioned contact members, two independent levers mounted adjacent to said movable contact members and each having parts to engage the corresponding movable contact members and actuate the same, a spring acting on each of said levers to move the same in one direction, a manually actuated device to control the movement of said levers by said springs and to move said levers against the action of said springs either in unison or with relation one to the other, and means for moving one of said levers independently of said manually actuated device.

19. In a device of the character described, a plurality of contact members, a corresponding plurality of movable contact members held normally out of engagement with the first mentioned contact members, two independent levers mounted adjacent to said movable contact members and each having parts to engage the corresponding movable 110 contact members and actuate the same, a spring acting on each of said levers to move the same in one direction, a rotatable member having cam shaped portions acting on said levers to cause the same to be moved either in unison or with relation one to the other, and means for moving one of said levers against the action of its spring and beyond the position determined by said rotatable member.

20. In a device of the character described, a main frame, an insulating plate carried by said main frame, a plurality of contact members mounted on said insulating plate, a plurality of resilient contact arms mounted 130

- on said insulating plate and arranged normally out of contact with the respective first mentioned contact members, independent levers pivotally mounted between their ends on said main frame and each having at its ends parts to engage the respective resilient contact members, and means to move said levers either in the same direction or in different directions.
- 10 21. In a device of the character described, a main frame, an insulating plate carried by said main frame, a plurality of contact members mounted on said insulating plate, a plurality of resilient contact members mounted on said insulating plate and ar-

ranged normally out of contact with the respective first mentioned contact members, a lever pivotally mounted between its ends on said main frame and having at its ends parts to engage the respective resilient contact members, a spring to move said lever in one direction, and a cam shaped device to limit the movement of said lever by said spring and to move the same against the tension of said spring. 20 25

In testimony whereof, we affix our signatures hereto.

JOHN E. KENNEDY.
CLARENCE E. MORFORD.
